UNITED STATES PATENT OFFICE

2,641,923

GAS GRAVITOMETER

Sydney William Binckley, Hollywood, Calif.

Application June 18, 1951, Serial No. 232,191

2 Claims. (Cl. 73—30)

1

The present invention constitutes an improvement upon that type of gas gravitometer described in United States Letters Patent No. 2,106,966 issued to George S. Binckley on February 1, 1938.

An object of the present invention is to provide a gas gravitometer of great accuracy, and which in its operation is substantially free from errors due to temperature variations, which corrects for humidity and gives a true specific gravity of the gas sample.

A further object is the provision of a gas gravitometer adaptable to various ranges of specific gravity.

The present gas gravitometer utilizes two columns of equal height, one of which has a continuously flowing sample of the gas passed therethrough, while the other column contains dry air, the difference of weight between the dry air and the gas in these two columns being measured and recorded in terms of specific gravity. With reference to the foregoing, ordinarily the weight of the gas sample is expressed as a percentage of the weight of the atmosphere as it exists at the time, which includes water vapors which may be present in the atmosphere. Since air containing moisture has less density than dry air at the same barometric pressure, variations in atmospheric humidity above or below that existing at the time the gravitometer is calibrated, will introduce errors in recorded gravity of the gas samples. The construction and arrangement of the present invention overcomes this error.

Furthermore it has been determined that the effective height of the gas column whose weight is to be determined may be slightly increased or decreased during operation of a gas gravitometer, thus introducing an error. Accordingly, the present invention provides means whereby such an error in the determination of gravity is effectively eliminated.

A further object of the invention is to provide in a single gas gravitometer means whereby the gas gravitometer may be quickly adapted for use with gases lighter than air, or with gases which have a specific gravity of 2½ times or more than that of air.

Other objects of the invention consist in a gas gravitometer which is superior to gas gravitometers now known to the inventor, accurate in operation, easily installed and calibrated and substantially fool-proof in operation.

In the drawing:

Figure 1 is a front elevation, partly in fragment and in section, showing the gravitometer of the invention;

2

Figure 2 is a side elevation, partly in fragment and in section, of the gravitometer shown in Figure 1 and looking in the direction of the arrow 2 of Figure 1;

5 Figure 3 is a fragmentary, partially sectional, elevation of the gas and air columns used in the practice of the present invention;

Figure 4 is a perspective view of a weight member utilized when periodic change of the specific 10 gravity range of the invention is desirable;

Figure 5 is a sectional view on the line 5—5 of Figure 4;

Figure 6 is a schematic flow diagram of the 15 gas gravitometer; and

Figure 7 is a front elevation of the gas gravitometer within its case.

Referring now with particularity to the drawings, reference is made to Figure 6. In said figure I have provided two bells, to wit, a working bell 1 and a balance bell 2, both of which bells are of identical construction and size and preferably of the same weight, each bell having a curved or cylindrical side wall 3 and a conical top 4, the bell being open at the bottom. Each bell is adapted to be in part received within separate tanks 5 and 6. Each tank has a circular side wall which spacedly surrounds its respective bell and the two tanks communicate at 7, to provide a fluid passageway. It is intended that both tanks should be filled to a certain level with a liquid, such as a white oil.

Both bells are suspended from a beam 8 and the beam 8 by means of linkage 9 is adapted to actuate a pen arm 10 for movement over a graduated chart at 11, which chart is rotated by a clock indicated at 12.

A pair of vertical columns are provided at 13 and 14, the columns being of equal height. The column 13, in addition to the vertical portion, 35 has a lateral portion 15 and a further vertical portion at 16, which is central of the tank with its open end positioned above the level of the sealing liquid 17 in said tank. The column 14 is similarly arranged in that it has a lateral at 18 and a short vertical portion 19 connecting with the lateral, the open end of said vertical portion 19 being above the level of the liquid 17 within said tank and bell. The gas sample whose gravity is to be determined is passed through a tubing 20, the said tubing carrying a drop tube 21 extending below the level of a liquid, such as oil 23, contained in bottle 22, so that the rate of flow of gas through orifice plug 28 is constant—that is, fluctuations in pressure of gas in tube 20 result in increase or decrease in rate of flow through tube 21, but do not affect the rate of

gas flow in tube 20 after the gas has passed the junction of tubes 20 and 21. Outlet tube 24 functions as a vent to carry away gas from bottle 22. The tube 23 is bent at an angle to provide a vertical portion 25 and said portion 25 is passed centrally within the portion 16, with the outlet from said tube communicating with the space included between a pair of diffuser plates 26 and 27. An orifice plug is included within the pipe portion 25 at 28. As the specific gravity of the gas is determined with reference to dry air, in other words, the difference in weight between dry air and the gas, I provide a tubing 29, which has two vertical portions as shown at 30 and 31, with an inter-connecting pipe at 32, the portion 30 being passed centrally of the portion 18 and communicating between the two diffuser plates 33 and 34. The length 31 of the tubing 29 is in direct communication with the case 35, at one end thereof, the case having an intake tube at 36. This case is adapted to hold a material such as a silica gel for the purpose of removing moisture from the air passed through said case and into the tube 29 for reception between the diffuser plates 33 and 34.

The brief résumé of the working elements of the invention has been set forth and it is evident that the flowing gas sample passing through the tubing 20 has its pressure regulated by the bottle 22 and that the gas is continuously received within the working bell 1 above the level of the liquid 17 and that the air is dried prior to said air being received within the balance bell 2 above the surface of the liquid 17. The weight of the gas in bell 1 and in gas column 13 is balanced against the weight of dry air in bell 2 and dry air in column 14.

Reference will now be made to Figures 1, 2 and 3, which specifically show the structure of the invention. It will be noted that I have provided a base 39 upon which the various elements of the invention may be mounted. For instance, the tank members 5 and 6 are provided with depending feet 40, which may be secured by means of bolts or screws 41 to the base. Furthermore, the columns 13 and 14 may be anchored to the base, or secured within sleeve fittings, as shown in Figures 2 and 3, at 42. As the device should stand vertically, with the base horizontal, for best operating characteristics, I may provide a bubble type level, not shown. In addition, leveling screws 43 are passed through the base so that accurate adjustment of the base and the instruments carried thereon may be obtained. These features are mere refinements and do not constitute a part of the invention.

It will be noted that the tubing 20 for conducting the gas sample to the working bell and thence to the column 13 has a slightly different arrangement from the schematic showing in Figure 6, in that the pressure regulating bottle 22 is held suspended in front of the tanks 5 and 6, the tubing 20 being provided with fittings carried by the cover 44 of said regulating bottle. Also the tubing 20 communicates with a fitting leading to a pipe here designated as 20-a, which pipe has a fitting connecting with a pipe 20-b, which pipe enters an enlargement 45 external the base of the tank 5. The portion 15 for the column 13 likewise has connection with said enlargement 45. Thus in place of the portion 15 being passed through the side wall of the tank 5 as shown schematically in Figure 6, in actual practice this portion is below the base of said tank as shown in Figures 1 and 2. The enlarge-

ment 45 carries portions 16 and 25, which portions are central of the tank and extend upwardly therein for communication with the interior of the working bell. The enlargement 45 carries a drain plug 46 which permits drainage of that portion numbered 16, which communicates with the column 13. A like construction is provided for tank 6, wherein the base has an enlargement 47, which communicates with the column 14, which enlargement carries a drain plug 48, with the pipe 32 communicating with the interior of the enlargement and extending centrally of the portion 19 which communicates with part 18. Included within the portion 31 of pipe 29 is a valve 49 and the valve in turn is secured to the case 35. This case is cylindrical in form and provided with a screw cap 50. A tube 36 extends from the cap and within the case is placed some air drying medium such as silica gel, as indicated at 51.

The beam 8 carries adjacent its ends bearing spools 52 and 53 and links 54 and 55 at one end are provided with knife edges for contact with said spools, the opposite end of each link being received within the slot of a stud carried at the apex of each bell, as shown at 56. A screw 57 is passed through each stud and a link so that each link will suspend a bell when the links are engaging the spools 52 and 53 of the beam. The beam is centrally secured at 58 to a cross head 59 (see Figure 2), the cross head being supported by a pair of fixed fulcrum links 60 and 61, which links depend from portions 62 and 63 of a bracket 64, which bracket is provided with a collar 65 surrounding a portion of the column 13 and held thereto by means of set screws 66. Connection between the fixed links 60 and 61 with the beam 59 is by means of knife edges so that the beam may tip during movement of the bells 1 and 2.

The cross beam 59 is provided with a cylindrical portion at 67 and a clamp ring 68 surrounds this portion. Depending from the ring is a pendulum rod 69, and diametrically positioned therefrom is a rod 70 carrying a weight 71. Secured to the pendulum rod is a thermostatic coil 72 adapted to raise or lower the position of a pendulum weight 73. The construction of the elements just referred to is shown in full in the Binckley Patent No. 2,106,966, heretofore referred to.

A collar 74 is carried by the column 13, which collar has a lug 75 to which is pivotally secured member 76, the outer end of which member is bifurcated or slotted so as to receive the pendulum arm and hold the same against movement in what is termed the zero stop position.

The bracket 64 is formed to carry at its forward end the clock 12 and a chart plate 77, the actual chart 11 being secured to the chart plate by means of a nut 78 carried on a hub which is rotated by the clock shaft.

A collar 79 is secured to column 13 and carries a bracket 80. Posts 81 and 82 extend from one side of this bracket. Posts 81 and 82 both carry adjustable pivot screws 83, with a shaft 84 held therebetween. A lever 85 is secured to shaft 84, the said lever provided with an adjustable weight 86. One end of the link 9 is secured to the lever 85 while the opposite end of said link has a fitting which is pivotally secured to the beam 8 adjacent one end thereof. The pen arm 10 is provided with a fitting 87, see Figure 1, which is secured to the shaft 84. The arrangement is such that the pen arm may be swung relative to the fitting from the plane of the chart 11. As is

usual, the outermost end of the pen arm carries a pen 10-a. The shaft 84 carries an adjustable balancing weight, designated generally as 88.

As a device of this character must be carefully calibrated, other balancing weights are provided. For instance, the beam 8 carries an adjustable weight 89, actuated by a vernier 90, which aids in balancing the beam and its associated parts, such as the working bell, the balance bell, together with linkage, to a zero position. Other weights shown at 91 and 92 are adjustable upon a rod 93 secured to the clamp ring 68. As this clamp ring is associated with the pendulum, it is essential that the pendulum be properly balanced to a zero position. As an aid in this balancing, adjustable weights 94 and 95 are mounted on a rod 96 extending from the cross head beam 59.

A feature of the present invention resides in the arrangement of the columns 13 and 14. The lower ends of the columns 13 and 14 are fitted within members such as shown at 42 in Figure 2 for the gas column and a like member for the air column, and preferably the gas and air columns are welded to said base fittings. A clamp 100 is secured to both columns, the clamp being held by set screws 101. The clamp is provided with a lug 102 which has a transverse bore to permit passage therethrough of an elongated screw-threaded rod 103. Lock nuts 104 and 105 are carried on the screw threads of the rod 103 and on each side of the lug. The said screw-threaded rod carries an adjustable pointer 106 adapted to play over a barometric scale 107 secured by clamps 108 and 109 to the column 13. The upper end of said screw-threaded rod 103 is secured to a stud 110, which stud extends outwardly from a cap 111 carried on the columns 13 and 14. This cap is so formed as to provide two annular flanges 112 and 113. Sleeves 114 and 115 surround the upper portions of the respective columns 13 and 14, with the lower ends of said sleeves fitted within the flanges 112 and 113. The upper end of sleeve 114 is internally screw threaded at 116 and a tubular gas cap 117 is threaded thereto. A spacer 118 is provided between the lower end of said cap and the upper end of the sleeve 114. Also to limit the threading between said cap and the said sleeve, the said cap is provided with an internal ring 119. The upper end of the gas cap has an annular top 120.

The sleeve 115 is externally screw threaded for engagement with the threads of what is termed a lower air cap 121. This cap is threaded to the lower end of an air column casing 122. The lower air cap 121 is provided with a screen 123, and the top of said air column casing 122 is provided with a screen 124 and a reduced opening 125. The air column casing houses a material 126 adapted to prevent entry of moist air into the column, which material may be silica gel.

Weights of the character shown in Figure 4 may be utilized in the invention to increase the specific gravity range of the instrument. The weights constitute in each instance a disk 127 formed with a central bore 128 and a counter bore 129. The disk is provided with an annular flange 130 and with a radial slot 131. The arrangement is such that a weight may be positioned on a stud 56 as shown in Figure 1, the links 54 and 55 being passed through the radial slot 131, with the top of the stud fitting within the counter bore 129. A radial bore is provided

at 132 for receiving a plug type weight, if necessary, for proper calibration. The arrangement is such that a further disc 127 may be added, the flange 130 fitting within its counterbore 129.

5 The operation, uses and advantages of the invention just described are as follows:

In the adjustable type gas and air columns, air driers are provided for the air column and for air which enters the tubing 29 to be received within the balance bell. The adjustable air and gas columns have certain advantages over a column that is not adjustable. Particularly the adjustment permits compensation for barometric pressure changes. It is evident that the instrument of this invention may be used in different localities and barometric pressure change becomes very important.

The balance bell is used for balancing the weight of the working bell and both bells are 20 immersed within the sealing liquid 17, the sealing liquid surrounding both bells and likewise being received within the same as illustrated in Figure 6. Hence surface tension and buoyancy of the sealing liquid is not a factor.

25 In the type of instrument shown, two columns are used, one column for the flowing gas sample whose specific gravity is to be determined with relation to dry air, and a second column having said means both at the entrance and exit for said column to dry the ambient air. Movement of the two columns is simultaneous as both columns are of the same length and such movement is indicated on the barometric scale 107, movement occurring when the nuts 104, 105 are 30 loosened on the threaded rod 103 to raise or lower both said columns and to lock them in a specific position. Obviously, the columns are adjustable in height to compensate for barometric pressure changes. As shown, the columns extend within the sleeves 114 and 115 for a 35 considerable distance so that the columns have quite a range of movement. The present two column arrangement with adjustability for height of both columns simultaneously provides a means which allows the columns to be moved easily 40 and without the necessity of changing fixed length columns.

45 To change the range of the gravimeter for different specific gravities, the weights shown in Figure 4 may be utilized to raise or lower the specific gravity range of the instrument. Thus, assuming that both columns have been fixed as to height, the weight shown in Figure 4 may be placed over the stud of the working bell. 50 Thus, with a range of weights, the instrument may be made to record from zero to .5 or by changing the weights from .5 to 1.0; 1.0 to 1.5; 1.5 to 2.0 to 2.5.

The vernier type weight provided for the 55 beam 8 at 89 and 90 is important, in that air balance or zero setting is made by adjusting the position of said weight, to the end that the beam is in equilibrium with the pen which plays over the chart at point 1.0.

60 We will not attempt here, in the statement of operation, to go into calibration of the instrument, although it is evident that the same may be calibrated quite easily by adjusting the weights connected with the various parts which include, of course, the pendulum and its thermally controlled weight.

In operation this instrument utilizes, as before stated, the difference in weight between a column of gas and a column of dry air of 65 equal height. The entire interior of the gas

column and the working bell 1 is filled with gas while the dry air column and the balance bell are filled with dry air. These two columns are of exact height and the bells are of exact diameters. Therefore, the difference in weight of the two volumes is a major force acting on the working bell and tending to raise or depress it, as the gas is heavier or lighter than dry air. This force is resisted by the weight of the pendulum which moves and allows the pen mechanism to move in direct ratio to the specific gravity of the gas sample. The rate of flow through the gravimeter is approximately 2 cubic feet per hour. Thus, the gas within the instrument, theoretically, is completely changed about 19 times every hour, or about once every 3 minutes. Thus the time lag is short and complete purging is rapid.

In order that no error be introduced by temperature variations, the pendulum weight is mounted on an arm which in turn is attached to one end of the thermostatic coil, at 72 and 73. This coil and assembly is so calibrated that the center of gravity of the weight is raised or lowered in direct proportion to the change in the air-gas differential, due to a given temperature variation. Even under extreme conditions of temperature change, the record made by this instrument is that due to the working force acting on the head of the working bell, which would exist if the temperature were constant at 60° Fahrenheit. The pendulum weight alone, and not the entire assembly of its supporting elements, resists forces acting on the working bell. The working bell and the balance bell, of course, are placed at equal distances from the fulcrum of the beam from which they are suspended. The balance bell functions to balance the weights of the working bell and also functions to compensate the effect of the buoyant force and surface tension of the sealing liquid 17. As the bells are of the same diameter, the surface tension of the liquid may vary to any extent without having any effect whatsoever upon the calibration. Ordinarily extreme changes in humidity would have a definite bearing on the recorded gravity on the chart. However, the present invention in utilizing a double column with dry air is not affected in any manner by changes in

humidity and the record as recorded on the chart is the true specific gravity of the gas corrected for temperature and humidity.

I claim:

- 5 1. A gravimeter, including a tank holding a sealing liquid, a working bell and a balance bell immersed in part in said sealing liquid to provide an enclosed space in each bell, a balance beam supporting said bells, means for directing a flowing gas sample within the enclosed space of the working bell, means for directing dry air into the enclosed space of the balance bell, a pair of elongated columns the tops of which are above the level of the sealing liquid, one 10 of which communicates with the enclosed space within the working bell and the other of which communicates with the enclosed space within the balance bell, and compensating means comprising means for simultaneously varying the length of each column.
- 15 2. A gravimeter including a tank provided with a sealing liquid, a balance bell and a working bell immersed in part within the said sealing liquid to provide an enclosed space 20 above said liquid in said working bell and in said balance bell, means for directing air within the balance bell into the enclosed space and means for preventing the entrance of moist air within the balance bell, means for directing a gas sample within the enclosed space of the working bell, a pair of columns, the tops of which are above the level of the sealing liquid, one column of which communicates with the enclosed space in the working bell and the 25 other column of which communicates with the enclosed space in the balance bell, and means in the column communicating with the balance bell for preventing the entrance of moist air within said column.
- 30 3. A gravimeter including a tank provided with a sealing liquid, a balance bell and a working bell immersed in part within the said sealing liquid to provide an enclosed space 35 above said liquid in said working bell and in said balance bell, means for directing air within the balance bell into the enclosed space and means for preventing the entrance of moist air within the balance bell, means for directing a gas sample within the enclosed space of the working bell, a pair of columns, the tops of which are above the level of the sealing liquid, one column of which communicates with the enclosed space in the working bell and the other column of which communicates with the enclosed space in the balance bell, and means in the column communicating with the balance bell for preventing the entrance of moist air within said column.

40 SYDNEY WILLIAM BINCKLEY.
